Ferdinando Hilti

8198 X Letters Patent.

The Schedule referred to in these Letters Patent, and making part of the same, containing a description in the words of the said Ferdinando Hilti, himself of his improvement in a machine for the purpose of breaking of hemp and flax.

To all to whom these presents shall come:

Be it known that I, Ferdinando Hilti of the Town of Franklin County of Williamson and State of Tennessee, have invented a new and useful machine for breaking of hemp, and flax and that the following is a full and exact description of the construction and operation of the said machine associated and put in operation by me at my place of plantation in this County, viz. The brake which I had put up at my plantation during the last autumn, consists of two parts which I call male and female or running and stationary frames. The stationary frame is constructed after the following manner. The base or bottom consists of two pieces of scuttling placed parallel and opposite to each other and securely joined together by two cross bars of the same description of scuttling, this base or bottom is 13 feet long and 4 feet wide and the thickness of which it is made 8 inches wide and 5 inches thick. upon each of the long scuttling stand three uprights 4 feet apart, and the frame being 4 feet wide makes them 12 feet apart in a row. These uprights are three feet in height of timbers of timber 5 & 6 inches wide and three inches thick standing the broad way across the long timbers of the base. At 8 inches from the base each of these uprights are shouldered on their outer sides two inches deep, and extending to their upper extremities. These shoulders are for the purpose of receiving and supporting the arms of the male portion of the brake. At eight inches above these shoulders the uprights are cut into notches to fasten on the arms

uppon a longitudinal timber of the stationary frame, these timbers are 10 feet 10 inches long 5 inches wide and 11 inches thick. Justly these uprights terminate in blocks about 8 inches square being held on the upper edge back three in number 8 feet 5 inches long 6 inches wide by two and a half inches thick. The middle set of uprights are braced each way forward and back. Across the front of each of the uprights just below the blocks for the upper longitudinal timbers and opposite to the part intended to receive the running frame, blocks are taken out to the number desired, say 3, 4, 5 or more one inch deep, one inch wide and about one inch and a half apart, to receive the slats which constitute the female or stationary part of the brake. Into these mortises are resting places thus formed, are fitted the back parts of the slats, these slats are made of hickory timber split out and deeped down to about one inch in thickness on their backs, and diminished to a half inch in front. They are about 3 or 4 inches wide and four feet long, and fitted into the places designed for them in the uprights. These female slats being fitted to their places are made fast in them, by means of plates of iron in number one over each end of each set of plates. These plates are 10 inches long 11 inches wide, and a quarter of an inch thick. They are fitted over the fronts of the slats by cutting off them down in front, in the form of a shoulder so that the plates rest on them all level, through each of these plates of iron run two bolts which passing also through the uprights made secure by two lugs on their extremities. In the basement frame of the brake, are three hickory brace pieces of plank 18 feet long and 18 inches broad; these are situated in the rear of each set of uprights, and are designed for the laborers to stand on. This constitutes the whole of the female or stationary portion of the machine. I will now describe the male portion of the running frame, this consists of two pieces of beamling 18 feet 5 inches long 7½ inches wide, by two and a half

is half inches thick, framed together by mortising and being made up in
 number 16 feet 5 inches long, 2 inches wide and 2 $\frac{1}{4}$ inches thick.
 Two of these are to be the back board and in the rear of this is
 a perspective sort of slate, passing through the runners so as to be kept
 in the outside. The front back is in front framed in the same
 way, and covered with the weight bearing scaffold to enclose the
 iron bar that holds the pilum. These front bars are given
 with greater security and strength by means of a couple of iron
 bolts that run through them, and bind them both together
 on each side of the back board that holds the pilum, at such
 distances these runners receive the male slate by sets of two
 three or more slate for each set; this running frame with its
 sets of words or slates and cross bars are so framed and fitted
 as to extend the before described stationary frame, and
 rest on the shoulders of the latter. The machine that has
 been constructed, having been designed for experiments, con-
 sists of three brakewheels each constituted to accommodate two or three
 slates, three slates like those of the stationary frame, are of
 hickory timber about one and a half inches thick on the
 back part and tapering in front to a half inch made round
 & smooth on the edges, and between three and four inches so
 broad. The ends of these slates terminate in two iron bars
 passing through the sides of the runners each way, and these
 bars stand fast by means of their shoulders in the inside
 and the ends of the scaffold are on the outside of the runners
 that are of the scaffold of the running frame which stands
 in the rear informed with braces. This constitutes the
 whole of what bears the male portion of the machine,
 this machine is propelled by a old power by means of a wind
 lass on the upper extremity of the shaft of a water wheel,
 over rotation of the wheel then by the aid of the pilum
 gives a play of 15 inches to the running frame. This running
 frame with its sets of male slates are placed in such relation
 to the

is the formate state of the stationary frame that at every revolution the two sets pass into the other and recede again; much labour now takes his hand on the broad plank so placed on the basement of the stationary frame and with both hands feeds the machine first holding the lump by one extremity and then by the other, shaking of it occasionally until he sees that it is well broke and freed from herbs. he then holds it to the attendants or lays it aside and takes it to another tier of the raw material. I propose to have three or four brakes to each machine, to put one hand to each brake, and to let a fourth or a fifth as the case may be, wait on the whole, to handle the raw material and to lay aside the clean sweep. From the experiments that I have made with the machine now in operation at my plantation, I am satisfied that it may be equally well put in motion by horse or steam power, I am also convinced that it may be increased or diminished on the same plan as to employ about 1000000 £. 3. 16. 5. or more hands according to the power that can be brought to act on it. I have learnt from actual experiment that the machine will do a good business at 200000 sticks or revolutions in the minute, and that its operations increase with the velocity of its movement, that the proper principle for regulating its speed is the speed at which a hand can feed it, which is near 100 sticks in the minute for the purpose of lessening the friction, the wear and the power necessary to propel the machine. I propose to rest the runners on friction wheels placed on the shoulders of the uprights, or on metallic plates, also plating the under surface of the runners with iron or other metal. Specifications.—What I claim as my own invention and not previously known in the above described machine is the plan of running a brake in the horizontal manner, and so counteracting of it at each side three or more brakes at the same time and the

the same frame. The advantage that I conceive to exist in my mode of confining the slate, is that it allows them to swing while they are still held fast, each to its place, and the facility with which one is taken out and another substituted in its place, when it becomes necessary to shift them. The slate of my brakes are all diminished in thickness from either extremity to the centre, so as to enlarge the spaces between them in the central portion while they approach towards either end.
